(54) **MARBLE, OR PIPE STONE TURNER**

(76) Inventor: **David Clark**

*David Clark, a citizen of
Letters Patent.*

The schedule referred to in these Letters Patent are making part of the same, containing a description in the words of the said David Clark himself of his marble and pipe stone turners.

There is a vertical bogwheel on a horizontal shaft of the machine which is turned by water or other force and conveys motion to a mandrel head standing upright the mandrel head turns by a nut or small spur wheel or vertical auger for boring stone for pipes for aqueducts or other purpose and it also turns the bit, or instrument for boring out the hollow in stone vessels of every description by means of a spur wheel and pinion on the perpendicular shaft of the bit. The stone to be bored by this last mentioned bit is placed in a box or hong of water under the bit. On one side of the machine is an ordinary Lathe, turned by a strap which passes round the first vertical wheel and round a wheel or pully on the Mandrel of the Lathe the rest for the chisel or turning tool is secured to the tool and projects beneath it. In all cases where a tough stone can be used for the stone to lie in whilst turned over it must be so placed; and in other cases kept constantly during the operation. This machine is for manufacturing Bowls, plates, mortars and mugs or flat or hollow ware of every description out of stone or marble as also for boring and turning aqueduct pipes, Bannisters stones &c. The number and kind of bits or bores are varied according to circumstances.
